(57) **CLAIM**

The ornamental design for a combined pet feeder and waterer, as shown and described.

DESCRIPTION

FIG. 1 is a front perspective view of the first embodiment of a combined pet feeder and waterer showing the pet waterer; FIG. 2 is a side elevational view thereof;

FIG. 3 is a top plan view thereof;

FIG. 4 is a front elevational view thereof;

FIG. 5 is a rear elevational view thereof;

FIG. 6 is a bottom plan view of the water container portion of the pet waterer shown separately for clarity of disclosure; FIG. 7 is a front perspective view of a second embodiment of a combined pet feeder and waterer showing the pet feeder; FIG. 8 is a side elevational view thereof;

FIG. 9 is a top plan view thereof;

FIG. 10 is a front elevational view thereof; and,

FIG. 11 is a rear elevational view thereof.
